EVAPORATOR FOR REFRIGERATING APPARATUS

William D. Collins, Evansville, Ind., assignor to Servel, Inc., New York, N. Y., a corporation of Delaware

Application May 17, 1932, Serial No. 611,829

1 Claim. (Cl. 62—126)

This invention relates to evaporators made of pressed or stamped sheet metal, and it is an object of the invention to provide an evaporator of this type having a plurality of freezing compartments which will accommodate different size containers. The invention, together with the objects and advantages thereof, will appear upon consideration of the following description taken in connection with the accompanying drawings forming part of this specification and of which:—

Fig. 1 is a front elevation with parts broken away illustrating one application of the invention;

Fig. 2, a side elevation;

Fig. 3, a detailed section on the line 3—3 of Fig. 2;

Fig. 4, a vertical section on the line 4—4, of Fig. 1; and

Fig. 5, a horizontal section on the line 5—5 of Fig. 4.

Referring to Figs. 1—5 of the drawings, the evaporator comprises an outer corrugated sheet metal shell 10, and an inner shell formed of a plurality of individual sleeves or casings 11, 12, and 13. The inner shell may be formed of any number of sections in the present instance 7 being shown, and each being adapted to receive a tray or container of a corresponding size, whereby each tray may be individually refrigerated on all four sides. The inner and outer sections are united by welding or any other desired means at their extremities, to form a closed chamber for refrigerant between the shells and a header 14, is provided at the top along the center and between the outer and inner shells.

The header 14 is substantially cylindrical in shape, formed by an upwardly curved portion of the outer shell and cooperating similarly 40 curved depending portions of the uppermost inner shells 11. Corrugations 15 are provided in the outer shell and extend at right angles from the header 14 and form refrigerant channels or passageways extending from such header.

The outer shell is shown as constructed of a single sheet of metal welded longitudinally along the center of its bottom, thus limiting the length of the channels extending from the header. However, the channels may and are preferably 50 made continuous, so that refrigerant may flow entirely around the exterior of the inner shell. The upper shells 11, may also be provided with short corrugations 16, extending from the header in opposed relation to the corrugations 15,

to afford enlarged communication with the header at the entrance to the channels formed by the corrugations.

The sleeves 11, 12, and 13 correspond in length to the length of the evaporator, and are nested together in the manner shown, and are not only welded at their ends where they engage the outer shell, but are welded entirely around each end to enclose fluid-tight spaces around each of the inner shells. The shells 11, 12, and 13 are provided with vertical corrugations 17 and 18, and horizontal corrugations 19 and 20, which form refrigerant channels. The upper sleeves or shells 11, may be welded longitudinally in any desired location, but are shown welded longitudinally along the center of their bottoms at 21. In like manner the shells 12 are welded at 22, the enlarged lower shell being similarly welded at 23.

In order to increase their heat exchange surfaces the evaporator is provided with side fins 24, and top fins 25, such fins being formed in any desired manner, or shape. The fins 24 and 25 may be formed integrally in substantially L-shape if desired. Also the header 14 may be closed at its ends in any desired manner by closure members 26, and 27. The evaporator may be supported in any convenient way, as for example by four or more studs 28, which receive bolts extending through a wall portion of the cabinet.

It will be apparent to those skilled in the art that various changes may be made in the construction and arrangement without departing from the spirit of the invention, and therefore the invention is not limited to that which is described in the specification and shown in the drawings, but only as indicated in the following claim.

What is claimed is:

An evaporator fabricated of sheet metal to form a horizontally cylindrical header, two outer horizontally spaced vertical rows of fluid passages communicating at their upper ends with said header, an inner vertical row of passages extending from said header downwardly between said outer vertical rows but terminating short of the lower ends thereof, and a plurality of vertically spaced horizontal rows of liquid passages connecting said vertical rows of passages to form a single lower compartment, and a plurality of horizontally spaced upper compartments completely surrounded by fluid passages.
